UNITED STATES PATENT OFFICE.

OTTO PETERS, OF SUTHERLAND, IOWA.

DESIGN FOR A LAMP-CHIMNEY CLEANER.

SPECIFICATION forming part of Design No. 30,527, dated April 11, 1899.

Application filed March 15, 1899. Serial No. 709,211. Term of patent 14 years.

To all whom it may concern:

Be it known that I, OTTO PETERS, a citizen of the United States, residing at Sutherland, county of O'Brien, State of Iowa, have invented and produced a new Design for Lamp-Chimney Cleaners, of which the following is a description.

In the accompanying drawings, which form a part of this application, Figure 1 is a front elevation showing my new design, and Fig. 2 is a side view of same.

My design is formed from a single piece of round wire bent to form a curved line A, a shoulder B, a curved line C, and bent upon itself to form the loop D, the curved line E, shoulder F, and curved line G. The lines A and G curve outwardly from the shoulders B

and F, respectively, and are of corresponding lengths. On the ends of the wire or at the termination of the lines A and G are oval or egg-shaped blocks H.

The general contour of my design forms a letter V.

Having thus described my design, what I claim, and desire to secure by Letters Patent, is—

The design for a lamp-chimney cleaner, substantially as herein shown and described.

In testimony whereof I affix my signature in presence of two witnesses.

OTTO PETERS.

Witnesses:

OTTO KIRCHHOF,
PETER C. BARK.
